United States Patent Office

Des. 194,060
Patented Nov. 13, 1962

194,060

FLOOR LAMP

Richard S. Winter, Alexandria, Va., assignor to Inter-armco, Limited, Alexandria, Va., a corporation of Delaware

Filed Mar. 15, 1962, Ser. No. 69,277

Term of patent 14 years

(Cl. D48—20)

FIG.1

FIG.5

FIG. 1 is a side elevational view of the floor lamp showing my new design;

FIG. 2 is a side elevational view taken from the opposite side of FIG. 1;

FIG. 3 is an elevational view looking at the left side of FIG. 1;

FIG. 4 is an elevational view looking at the right side of FIG. 1; and

FIG. 5 is a top plan view.

The dominant features of my design reside in the portions shown in full lines.

I claim:

The ornamental design for a floor lamp, as shown and described.
